UNITED STATES PATENT OFFICE

FRANK MOSSBERG, OF ATTLEBORO, MASSACHUSETTS, ASSIGNOR TO MOSSBERG PRESSED STEEL CORPORATION, OF ATTLEBORO, MASSACHUSETTS, A CORPORATION OF MASSACHUSETTS

REEL

Application filed May 1, 1928. Serial No. 274,269.

This invention relates to a reel; and has for its object to provide a construction which may be manufactured efficiently and yet permit one of the heads to be easily and quickly removed.

A further object of the invention is the provision of a member rotatably mounted in the head which may interlock with a portion carried by the barrel by means of a relative 10 rotation of the parts.

A further object of the invention is the provision of depressions in the barrel with cooperating parts in the head to receive a cord for binding together the coils of wire on a 15 loaded reel before the head is detached and the wire removed from the reel.

The invention further consists in forming a depression in the barrel extending longitudinally thereof with slots in the head extending radially outwardly from a position adjacent the depression in the barrel through which a binding cord may be manipulated for securing together the coils of wire on the reel.

With these and other objects in view, the invention consists of certain novel features of construction, as will be more fully described, and particularly pointed out in the appended claims.

In the accompanying drawings:

Figure 1 is a top plan view of the head of the reel.

Figure 2 is a fragmental perspective view of the barrel and a portion of one of the heads.

Figure 3 is a section on line 3—3 of Figure 1.

Figure 4 is a section on line 4—4 of Figure 1 showing the wire represented on the reel.

Figure 5 is a fragmental detail of the mounting of the threaded member or nut in the removable head.

It is found in the construction of wire reels desirable to remove one of the heads to slide a package of wire or the like from the reel and in order to provide a construction by which this may be easily accomplished I have rotatably mounted a threaded member in the detachable head which may threadingly engage a portion extending from the barrel

and which may be easily manipulated by means of a handle and in order to bind the coils of wire on the reel together before sliding them from the reel, I have formed depressions in the barrel with cooperating slots 55 extending from the depression radially of the head, whereby the cord may be positioned in the depression before the wire is wound on the reel and after the winding is finished, its ends may be brought together by using the 60 radially extending slots in the head through which the cord may be conveniently manipulated; and the following is a detailed description of the present embodiment of this invention and illustrating means by 65 which these advantageous results may be accomplished.

With reference to the drawings, 10 designates the barrel portion to which is suitably secured a head 11 by means of welding or the 70 like and at the opposite end of the reel a head 12 is detachably mounted.

Extending through the barrel 10 is a sleeve 13 which is suitably welded to the head 11 as at 14. The opposite end of this sleeve is supported by a suitable web 15 and is threaded as at 16 at its end. The head 12 is provided with a rotatable threaded member or nut 17 which has a shouldered portion 18 engaging the outer surface of the head 12 and which 75 has a reduced neck portion 19 extending through an opening in the head 12 with a collar or ring 20 suitably secured to this neck portion 19 on the opposite side of the head 12 by welding as at 21 to rotatably mount 80 the threaded member or nut 17 in the head. Handles 23 extend from the nut 17 to assist in positioning it on the threaded end 16 of the sleeve to tightly bind the head 12 against 85 the end of the barrel 10, as illustrated in Figure 3. A stud 24 is fixed in the web 15 and extends through an opening 25 in the head 11 to prevent relative rotation of the head 90 and barrel 10.

A hole 26 is provided in one of the heads through which the inner end of the wire coil may extend to be fastened and at the outer periphery of the head is a similar hole 27 through which the outer end of the coil may 100

be passed to be suitably bent to fasten the coil in position.

The barrel is recessed as at 28 and each of the heads is slotted as a 29 intermediate the ribs 30 raised thereon, which slot is so positioned that it extends radially from the recess 28 in the barrel to a point short of the periphery of the head but which slot extends substantially the thickness of a package of wire wound upon the heel thus providing a construction whereby a cord 31 for binding the coils of wire may be laid in the recess 28 with its ends extending through the slots 29 and when the desired amount is wound upon the reel the ends of this cord 31 may be brought together by passing its end through the slots 29 and tied as at 32, illustrated diagrammatically in Figure 4 to bind the package 34.

I have provided three sets of cooperating depressions and slots by which the package 34 of wire may be bound in various positions to prevent its spreading or unwinding, it being apparent that any desired number of such means for binding may be provided.

The head may be centralized with relation to the barrel by a plurality of suitably positioned raised ears 33, as illustrated in Figures 1 and 2.

It will be observed that I have provided by my construction above described an economical and easily manipulative removable head for the reel by means of which construction a package of wire wound thereon may be bound and readily removed therefrom.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A reel comprising a barrel, a threaded portion carried by said barrel, a head having an opening through which said threaded portion extends, and a threaded member rotatably mounted within said opening and associated with said head and threaded portion for holding said head in assembled position.

2. A reel comprising a barrel, a head at each end thereof, a threaded portion carried by said barrel, and a threaded member secured to one of said heads and movable with respect thereto engaging said threaded portion and detachably holding the head on the barrel.

3. A reel comprising a barrel, a head, means for detachably securing said head to said barrel comprising a threaded portion carried by said barrel, and a threaded member rotatably secured in said head for engaging said portion.

4. A reel comprising a barrel, a head at each end thereof, means for detachably se-

curing one of said heads to said barrel comprising a threaded portion carried by said barrel, a threaded member rotatably secured in said head for engaging said portion, and means to prevent relative rotation of said detachable head and barrel.

5. A reel comprising a barrel, a head at each end thereof, means for detachably securing one of said heads to said barrel comprising a threaded portion carried by said barrel, a threaded member for engaging said portion, said member being secured to but rotatably mounted in the detachable head, and a handle portion secured to said threaded member for rotating the same to secure the head in place.

6. A reel comprising a tubular barrel, a head fixed to one end thereof, a sleeve fixed to said head at one end and extending through and beyond the barrel and threaded at its other end, a detachable head, a nut rotatably mounted in said detachable head and engageable with the threaded end of said sleeve to force said head against the end of said barrel and secure the same in position.

7. In a reel, a tubular barrel, a head fixed to one end thereof, a sleeve fixed to said head and extending through and beyond said barrel and threaded at its free end, a detachable head, a nut rotatably mounted in said detachable head and engageable with the threaded sleeve end to force said head against the free end of the barrel, and means for preventing relative rotation of said detachable head and said barrel.

8. In a reel, a tubular barrel, a head fixed to one end thereof, a sleeve fixed to said head and extending through and beyond said barrel and threaded at its free end, a detachable head, a nut rotatably mounted in said detachable head and engageable with the threaded sleeve end to force said head against the free end of the barrel, and means for preventing relative rotation of said detachable head and said barrel comprising a flange secured to said barrel adjacent the free end thereof, a pin in said flange, and a cooperating opening in said head.

In testimony whereof I affix my signature.
FRANK MOSSBERG.
